UNITED STATES PATENT OFFICE

2,053,595

SHIPPING CONTAINER

Samuel P. Belsinger, Atlanta, Ga., assignor to
 Belsinger, Inc., Atlanta, Ga., a corporation of
 Georgia

Application March 8, 1935, Serial No. 10,094

3 Claims. (Cl. 229—23)

This invention relates to the art of shipping container and is particularly concerned with the manufacture of a container from blanks of pulp board material, by utilization of a minimum of material for the purpose, the container in finished form having flat integral end surfaces presented to the lading and externally, so that the containers may easily slide one on the other.

A container of the general type is described and claimed in my United States Patent No. 1,983,265. The difficulties of manufacturing such containers from "pulp board material" (i. e., a pulp board product such as fibre board or corrugated board or even cardboard, and characterized by its strength of resistance to tension stresses and its relatively great yield and resilience in bending stresses and its relative weakness in shear and endwise compression, as compared with wood), have been set out in my aforesaid patent.

According to the present invention, a type of container is provided which has an even greater assurance against displacement or relative shifting of the two sections; and is constructed with the top and/or bottom wall in the respective section integral with side walls thereof.

An illustrative form of practicing the invention is shown on the accompanying drawing, in which:

Fig. 1 is a respective view of the closed and sealed container.

Fig. 2 shows the two sections of the container in superposed but not abutting position.

Figs. 3 and 4 are views showing the types of blanks employed for the illustrated container section.

In the drawing, the container is illustrated as formed of two sections which are of identical perimeter at their open ends, the container being closed by bringing the two sections into abutment at these ends. Each of the sections is formed of one blank as shown in Fig. 3 and two blanks as shown in Fig. 4. Each of these types of blanks is of simple rectangular shape. The blank of Fig. 3 has a central connecting section C1 which will become the top or bottom of the package, dependent on whether the section is employed at the top or bottom of the container. Adjoining the central section C1 are the two side sections S1 and S2 which become side walls of the corresponding sections. These sections are separated by the score lines 10 and 11, which may be formed in any desired manner thereon and serve to establish the reference lines

about which the folding will be accomplished. The blank of Fig. 3 also comprises flange portions which are each substantially of the length of the corresponding central and side portions. The side portion S1 has the two flange portions F11 and F12 integral therewith; the central portion C1 has the flange portions F31 and F32 integral therewith; and the side portion S2 has the flange portions F21 and F22 integral therewith. The flange portions are separated from the corresponding side portions by the scoring lines 12 which may be formed by a single operation on a normal scoring machine, for example. The individual adjacent flange portions are separated by gashes 13 which are substantially in alignment with the scoring lines 10 and 11.

For assembling a section, the several parts of the blank are folded at right-angles, in the same direction out of plane. A side wall blank S3 or S4 (Fig. 4) is then inserted so that the flange portions of the blank at the corresponding side are overlapping it and one another. These flange portions are then fixedly secured to the side portion S3 or S4. This securing is preferably accomplished by the standard stitching machine of commerce. Since the container section has an open end, the stitching can be easily accomplished, and the staples properly clinched at the inside of the container section.

It will be noted that the depth of the side wall portions S1 and S2 and their corresponding flange portions, is greater than the depth of the side wall portions S3 and S4 in the upper section of the container; while the reverse condition exists in the lower section. The offset, or differential of depth is the same, so that the two corresponding side walls or flange portions of the two sections are in abutment when the container sections are assembled together, so that there is abutment of the two sections substantially throughout their peripheries.

The flange portions of the upper section are illustrated as being the ones which are longer than the flange portions of the lower section. Hence, for example, the long flange portion F11 of the deep side S1 of the upper section overlaps and is secured to the adjacent side S3 of lesser depth, and projects beyond the lower edge 14 thereof. This upper flange F11 therefore also overlaps the deeper side wall S3 of the lower section. Hence, at each of the four vertical edges, the engagement of the flanges and side walls operates to prevent relative shifting of the two sections in a horizontal direction.

- The sections may be filled with any suitable merchandise such as package goods, textiles, etc., and the sections brought together in the aforesaid overlapping relationship. The edges 14, 15, and 16 at the open end of the upper section about throughout the perimeter of the section with the opposing edges 14a, 15a, 16a of the lower section, and serve for transferring at least a portion of the weight of superimposed containers.
10. The final closure is effected by a cemented strip T which may be a fabric or cloth tape, which is brought into position overlapping the corresponding side walls while they are in abutment and is secured thereto so that it may operate in tension.
15. for preventing separating movement of the two sections and likewise exerts a force for maintaining the opposing side walls in definite abutment. It will be noted that the container has a smooth top and bottom, so that the container may be slid 20 on the floor, or may have another container slid along its top. It can be manufactured substantially without waste. The sections are formed individually without any employment of cement, and the stitches are revealed, and any tampering 25 with the section is immediately revealed. The sealing strip T maintains the closure of the package and likewise reveals any attempt at tampering therewith. As it is applied while the sections are in abutting relationship, there is no considerable difficulty of securing a proper closure at the 30 abutting edges, and no great difficulty of penetration of cement is present.

As with the structure of the prior patent, the maximum effect of the valuable property of strength in tension of the material is advantageously employed, while its weaknesses are overcome by the particular arrangement of the parts selected so that such stresses are distributed over large areas, or may be transferred directly to the 40 lading in the manner described in the said patent.

I claim:

1. A shipping container of pulp board material comprising upper and lower sections of identical perimeter at the open ends; each section comprising an integral structure providing opposite side walls and a connecting wall, said side walls and connecting wall having integral flanges, and a pair of side wall members overlapping and secured to said integral flanges; at least one side 45 wall of one section and its corresponding integral flange having a different height than an adjacent side wall thereof so that said one side wall and its flange extends beyond said adjacent wall, the two sections having their side walls in abutting relation in the closed container with the said wall flange of a longer side wall on one section over-

lapping the longer side wall on the other section for preventing relative shifting of the sections and with each side wall of each section located substantially in a common plane with the abutting side wall of the other section; and means 5 overlapping the corresponding side walls of the sections and holding the sections against separation.

2. A shipping container of pulp board material comprising upper and lower sections of identical perimeter at the open ends; each section comprising an integral structure providing opposite side walls and a connecting wall, said side walls and connecting wall having integral flanges, a pair of side wall members overlapping said integral flanges, and stitches connecting said side wall members and flanges; at least one side wall of one section and its corresponding integral flange having a different height than an adjacent side wall thereof so that said one side wall and its flange extends beyond said adjacent wall, the two sections having their side walls in abutting relation in the closed container with the said wall flange of a longer side wall on one section overlapping the longer side wall on the other section 25 for preventing relative shifting of the sections and with each side wall of each section located substantially in a common plane with the abutting side wall of the other section; and means overlapping the corresponding side walls of the sec- 30 tions and holding the sections against separation.

3. A shipping container of pulp board material comprising upper and lower sections of identical perimeter at the open ends; each section comprising side walls and a connecting wall including 35 vertical corner flanges integral with at least two of the side walls and overlapping and stitched to the adjacent side walls for holding the parts of the section in assembled form; at least one side wall of one section and its corresponding integral flange having a different height than an adjacent side wall thereof so that said one side wall and its flange extends beyond said adjacent wall, the two sections having their side walls in abutting relation in the closed container with the said wall 40 flange of a longer side wall of one section overlapping the longer side wall on the other section 45 for preventing relative shifting of the sections and with each side wall of each section located substantially in a common plane with the abutting side wall of the other section; and a binding strip overlapping and cemented to the side walls at the abutting edges thereof for holding the sections against separation.

SAMUEL P. BELSINGER.
